ARCHIE MACPHAIL NIVEN, OF DETROIT, MICHIGAN, ASSIGNOR TO CONTINENTAL MOTORS CORPORATION, OF DETROIT, MICHIGAN, A CORPORATION OF VIRGINIA

SLEEVE-VALVE ENGINE-CYLINDER HEAD

Application filed July 25, 1927. Serial No. 208,189.

This invention relates to internal combustion engines and refers more particularly to the sleeve valve type of engine. In this type of engine the upper extremity of the sleeve 5 ordinarily works in a pocket formed between the cylinder head and cylinder. While the cylinder head is ordinarily jacketed for cooling water, the amount of available jacketing is limited due to spark plug location and general arrangement of parts. As a result the sleeve jacket tends to become overheated resulting in formation of steam pockets, carbon accumulation and general inefficient operation of the engine.

One of the objects of my invention resides in providing means for overcoming the above objectionable characteristics. To this end I have provided means associated with the cylinder head for causing a positive circulation of cooling water for cooling the cylinder head and sleeve pocket. It has been proposed to provide a cylinder head casting so cored with passages as to guide the cooling water in a circulatory path through the cylinder head. My invention provides a substantially similar circulatory path of increased efficiency for the cooling water and eliminates the necessity for coring the cylinder head to form the cooling water guiding 20 passages. I provide a member preferably in the nature of a sheet metal stamping attachable to the cylinder head for guiding the cooling water in the desired circulatory path. Thus my invention tends toward simplicity 25 of manufacture with consequent lessening of expense and relatively light weight as compared with a cast cylinder head.

With these and other objects in view my invention resides in the novel combination 40 and arrangement of parts more particularly hereinafter described and claimed.

Referring to the drawings in which like reference characters represent corresponding 45 parts,

Fig. 1 is a sectional elevation view through a typical cylinder head showing my invention,

Fig. 2 is a bottom plan view of the cylinder 50 head assembly, and

Fig. 3 is a perspective view showing my invention associated with the cylinder head.

In the drawings reference character A represents the engine having one or more cylinders 10 with associated piston 11 and sleeve 12, the latter for illustration being shown as the "Burt-McCollum" single sleeve valve type in which the sleeve is moved in a combined reciprocating and oscillating path with respect to the sleeve axis in moving the 55 sleeve ports to function with the usual cylinder ports.

The cylinder is closed at the top by a cylinder head B which may be formed with walls 13 and 14. The wall 13 together with the associated cylinder forms a valve pocket 15 accommodating the movement of the upper portion of the sleeve valve 12. The wall 14 is spaced from wall 13 to form the cylinder head cooling water jacket 16 and also defines 60 the combustion chamber 17. The wall 14 may be extended to provide a barrel 18 with the usual spark plug opening 19. The cylinder head B may be secured to the cylinder by studs 20 passing through openings 21, at 65 the corners of the cylinder flange 22, for engagement with the cylinder.

The cooling water from cylinder jacket 23 is open for communication with the cylinder head jacket 16 through opening 24 preferably along one side only of the cylinder head. For guiding the water from opening 24 I have provided a cylinder head water jacket cover C, preferably formed of a sheet metal stamping. The cover C may be formed 70 with side wall 25 spaced from the side of the cylinder head adjacent the opening 24, side walls 26, and top wall 27. The water in moving across the cylinder head is caused 75 to circulate downwardly into the jacket 16 by reason of the cylinder head baffles 28 which divide the jacket 16 longitudinally.

Cooperating with baffles 28 are side cover baffles 29 preferably formed integrally with the main body of the cover C. The top wall 27 may be formed with a portion 30 engageable with the barrel 18 and for convenient location may be secured in position by a barrel flange 31 which is ordinarily provided for supporting the water sealing ring 80 85 90 95 100

32 for the cylinder head top cover 33. A nut 34 threadedly engages barrel 18 for clamping the cover 33, sealing ring 32, and jacket cover C in position.

5 If desired the particular illustrated embodiment of my invention might be modified without departing from the spirit of the invention. For example if desired the side cover baffles 29 might be extended downwardly to replace the cylinder baffles 28 although little difficulty is experienced in casting the baffles 28. Other modifications will readily suggest themselves.

15 With my invention, the jacket cover C is constructed separately from the cylinder head affording a relatively great inlet area for the cooling water as at 34.

20 The cooling water may be circulated throughout the entire system by the usual water pump, the water being returned to the usual radiator by a header 35 on the outlet side of baffles 28 and 29. The general direction of water circulation through the cylinder head is illustrated by the arrows 25 in Fig. 1.

30 My invention is equally well adapted for use with various types of sleeve valve engines such as the multiple sleeve or single sleeve types.

35 What I claim as my invention is:

1. An internal combustion engine of the sleeve valve type comprising in combination, a water jacketed cylinder, a piston operable therein, a water jacketed cylinder head forming a sleeve pocket with the cylinder, a cylinder head water jacket cover cooperating with the cylinder head water jacket to provide a conduit for the cooling water, a cylinder head top cover forming a water header, 40 and means engaging the cylinder head for clamping the top cover in position and for maintaining the jacket cover in proper position.

45 2. An internal combustion engine of the sleeve valve type comprising in combination, a water jacketed cylinder, a piston operable therein, a water jacketed cylinder head forming a sleeve pocket with the cylinder, and a sheet metal cylinder head water jacket 50 cover formed with parallel side and parallel end portions cooperating with the cylinder head to form a cooling water conduit for the cylinder head.

55 3. An internal combustion engine of the sleeve valve type comprising in combination, a water jacketed cylinder, a piston operable therein, a water jacketed cylinder head forming a sleeve pocket with the cylinder, and a sheet metal cylinder head water jacket 60 cover formed with parallel side and parallel end portions cooperating with the cylinder head to form a cooling water conduit for the cylinder head, said jacket cover also provided with a top wall engageable with a portion 65 of the cylinder head.

4. A sleeve valve engine comprising in combination, a water jacketed cylinder, a water jacketed cylinder head having a substantially rectangular peripheral flange, means clamping said flange on the cylinder 70 end, a top cover positioned on said cylinder end in spaced relation with the cylinder head flange, and a cylinder head jacket cover co-operating with the cylinder head to form a water conduit therefor, said jacket cover having a side wall positioned on the cylinder end, in spaced relation with a side of said rectangular peripheral cylinder head flange providing an inlet from the cylinder jacket to the said cylinder head water conduit said 75 inlet extending substantially the length of the said adjacent side of the cylinder head flange.

5. A sleeve valve engine comprising in combination, a jacketed cylinder, a jacketed cylinder head closing the cylinder, a cylinder 85 head cover, and an element separate from the head and cover enclosed by the cover constructed and arranged to conduct a cooling medium from the cylinder jacket to the cylinder head jacket, said element provided with a downwardly flanged portion spaced to one side of the cylinder head, and extending substantially the length of the cylinder head to provide an inlet for the cooling medium from the cylinder jacket. 95

6. In a sleeve valve engine, a jacketed cylinder, a cylinder head having a jacket depending in the cylinder and having an upstanding barrel, a cylinder head cover through which the barrel extends, sealing 100 means for the barrel and cover, and a member surrounding the barrel beneath the cover overlying the cylinder head jacket and forming with the cylinder head jacket a water conduit receiving water from the cylinder jacket said member having water outlet openings. 105

7. In a sleeve valve engine, a cylinder, a cylinder head having a flanged portion seated on the cylinder and formed with a water jacket depending in the cylinder, and a water deflecting baffle over said depending water jacket extending upwardly and laterally to a position overlying the cylinder head flange. 110

115 In witness whereof, I hereunto subscribe my name this 21st day of July, A. D., 1927.

ARCHIE MACPHAIL NIVEN.
